UNITED STATES PATENT OFFICE.

ERNST KARL ROTHE, OF EISENACH, GERMANY.

FIELD-GUN.

SPECIFICATION forming part of Letters Patent No. 738,629, dated September 8, 1903.

Application filed February 8, 1903. Serial No. 141,709. (No model.)

To all whom it may concern:

Be it known that I, ERNST KARL ROTHE, engineer, a subject of the Grand Duke of Saxe-Weimar, residing at Eisenach, in the Grand Duchy of Saxe-Weimar and German Empire, have invented certain new and useful Improvements in or Relating to Field-Guns, of which the following is a specification.

My invention relates to improvements in or relating to field-guns.

The main desideratum in the support for field-guns is that it should be as light as possible and yet be constructed in such a manner that the parts regulating the recoil and the brake-cylinder, with its stuffing-box, spring, piston, and piston-rod should be sufficiently protected on all sides against foreign bodies and splinters of shells. This is effected in accordance with my invention by providing the upper carrier or support on its under side with a protective armor detachably secured to the upper carriage. The upper carrier and the said armor are separated by a free space from the brake-cylinder, so that the latter is protected by the armor against splinters of shells that may come from the outside or from below, and after having been entirely or partly detached it allows of easy access to the brake, and more particularly to the stuffing-box.

In describing the invention in detail reference is had to the accompanying drawings, forming a part of this specification, in which—

Figure 1 is a side elevation of the brake-protector set up. Fig. 2 is a longitudinal sectional view thereof broken away at one end. Fig. 3 is a section on line A B of Fig. 1. Fig. 4 is a section on line C D of Fig. 1. Fig. 5 is a side elevation of a modified form of brake-protector broken away at one end. Fig. 6 is a section on line E F of Fig. 5. Fig. 7 is a side elevation of the parts separated, and Fig. 8 is a section on line G H, Fig. 5.

In the construction shown in Figs. 1 to 4 the upper gun carrier or support σ is fitted at a suitable point with ribs or projections σ' , projecting outward or inward, said ribs or projections being intended to receive the lateral flanges u' of the under side armor u .

In order to enable the armor u to be easily detached from the upper gun-carrier σ , the flanges σ' do not extend throughout the entire length, but only form comparatively short strips σ' , separated by intervals σ^2 , and the flanges u' of the armor have corresponding intermediate spaces u^2 . It is then only necessary to slightly displace the armor u in a longitudinal direction in respect of the upper carrier σ in order to disengage the former from the ribs or projections of the latter, and thus enable it to be removed.

Fig. 3 represents a section on the line A B through the ribs or projections σ' and flanges u' , while Fig. 4 is a section on the line C D through the intermediate spaces $\sigma^2 u^2$, Fig. 1. 65

According to the modified construction shown in Figs. 5 to 8 the ribs or flanges σ' are arranged on the lower edge of the upper carrier, which is deeper than that shown in Figs. 3 and 4, and the armor u is accordingly 70 made rather flat in this instance.

The arrangement is otherwise the same as that of the construction shown in Figs. 1 to 4.

The armor u , according to the present invention, may be composed of any suitable 75 number of parts detachably secured to the upper carrier in order to facilitate access to certain parts of the brake-gear.

The arrangement described enables the entire brake-gear—that is to say, the brake-cylinder with stuffing-box, piston-rod, and drawing-spring—to be protected against foreign bodies and splinters of shells which could otherwise get into it from the outside as well as from below and at the same time enables 85 the protective armor u of the upper carrier σ to be easily removed, which considerably facilitates inspection of the brake-cylinder, access to the stuffing-box, and cleaning thereof.

Having now particularly described and ascertained the nature of my said invention and in what manner the same is to be performed, I declare that what I claim is—

In a field-gun carriage, a slide-frame pivoted to the main carriage consisting of vertical plates along the top edge of which the gun recoils, a recoil-check and recuperating means placed between said plates, spaced.

2
lugs on the bottom edges of said plates, and
an armor forming a bottom for said slide-
frame having flanges engaging said lugs to
support the armor-plate, said flanges being
5 cut away between the lugs, whereby on slight
longitudinal movement of said armor-plate
it may be disconnected from said slide-frame.

In testimony whereof I have hereunto set
my hand in presence of two subscribing wit-
nesses.

ERNST KARL ROTHE.
